UNITED STATES PATENT OFFICE.

MAXWELL L. REIDINGER, OF ELIZABETH, NEW JERSEY, ASSIGNOR TO THE SINGER MANUFACTURING COMPANY, OF ELIZABETH, NEW JERSEY, A CORPORATION OF NEW JERSEY.

NEEDLE-PICKING MACHINE.

Application filed April 18, 1924. Serial No. 707,410.

This invention relates to improvements in needle-making machinery and has for its primary object to provide improved mechanism for rapidly and accurately rearranging 5 a plurality of needles whereby all of the needle-points project in the same general direction.

A further object of the invention is to dispose the rearranged needles in a receptacle in substantial parallelism.

Other and more specific objects of the invention will be apparent from the following description and claims.

In the manufacture of needles, a number 15 of operations are effected by machinery requiring a definite relative position of the needles for presentation to the operative parts of each particular machine. While prior efforts have been made to provide 20 mechanism for automatically rearranging a group of needles whereby they are disposed in the necessary relationship, such efforts have not been sufficiently practical to replace the manual rearrangement of the needles. This manual operation is commercially 25 termed needle-picking, a term which will hereinafter be employed for the like operation automatically effected by the machine of the present invention.

30 The needle-picking machine constituting a preferred embodiment of this invention includes a hopper, provided with rotary needle-agitating fingers for separating the needles and having a travelling base which deposits the needles upon an inclined plate disposed adjacent one end of a substantially horizontal reciprocating-table. This table is provided with a plurality of guideways constituted by parallel guide-bars spaced from 35 each other a less distance than the length of the needles to be rearranged. These guideways insure the disposal of the needles, either point or shank first, substantially lengthwise in the direction of reciprocation of the table. 40 The table is reciprocated in a manner such that its movement in one direction is suddenly arrested, whereby the needles are advanced in their guideways a short distance during each reciprocation of said table. This reciprocating table is furthermore provided with a gap of adjustable width, said gap intersecting the path of travel of the needles 45 across the table.

50 It is a fact that the shanks of needles are

heavier than their blades and consequently 55 should the shank of a needle first approach said table-gap the needle as it passes the initial edge of the gap swings or tilts about said edge under gravity action and drops shank-first into a narrow chute terminating 60 in a detachable receptacle. Needles which approach said gap point-first are advanced across said gap because the greater weight of the shank when resting on the table prevents tilting of the needles about the initial 65 gap-edge. However, as soon as the needle-shank overlies the gap, the needle tilts under gravity action about the opposite edge of the gap and again drops shank-first into a chute. Inasmuch as the table is provided with a plurality of the narrow guideways and a chute is connected with each guideway, a large 70 number of needles may be simultaneously and accurately rearranged in the desired manner and consequently a single machine will effect 75 the same result as a large number of needle-picking operators. The table-gap may therefore be termed a needle-point direction determining device and is hereinafter so termed.

In the accompanying drawings, Fig. 1 is a 80 side elevation of a needle-picking machine constituting a preferred embodiment of the invention. Fig. 2 is a top-plan view of the same, omitting certain of the needle-agitating fingers and the needle guide-bars for the 85 sake of clearness. Fig. 3 is a rear end elevation of the machine. Fig. 4 is an enlarged sectional view of the rear portion of the needle-supporting table and its actuating mechanism. Fig. 5 is a perspective view illustrating 90 the operation of the needle-point direction determining gap. Fig. 6 is a sectional view of the delivery end of the needle-hopper and showing a portion of the table. Fig. 7 is a sectional view of the driving clutch. 95

Referring to the drawings, a machine constituting an embodiment of the present invention, is supported by standards as 1 and is constructed with a main rectangular frame 2. Journalized in alined bearings provided in 100 brackets 3 and 4 mounted upon the base of the frame 2 is the main-shaft 5 carrying a grooved belt-pulley 6. The pulley 6 is driven by means of a belt 7 passing under adjacent idler-pulleys 8 and 9 journalized to rotate upon a stud-shaft 10, parallel with the main-shaft 5 and sustained by a bracket 11, suitably secured upon one side of the frame 2. The belt 105

7 may be connected with any suitable power source.

A needle-hopper frame 12 is sustained by straps as 13 suitably secured upon side-bars 14 joined at the rear end of the machine by a cross-bar 15, the frame 12 being spaced from the side-bars 14 to provide clearance for a flat belt 16 constituting the base of the hopper. The belt 16 passes over drums 17 and 18, upon the forward drum 17 of which are secured the spindles 19 and 20 journaled in brackets, as 21, suitably secured upon the opposite sides of the machine frame 2. The spindle 19 carries a worm-wheel 22 in mesh with a worm 23 upon the upper end of a vertical shaft 24 journaled at its upper end in a gear-casing 25 and adjacent its lower end in a bracket 26 both provided upon the side of the machine frame 2. The vertical shaft 24 carries a grooved belt-pulley 27 connected by means of a belt 28 with a pulley 29 secured upon a short intermediate shaft 30 journaled in bearing-brackets, as 31, upon the frame of the machine. The shaft 30 also carries another belt-pulley 32 driven by means of a belt 33 from a pulley 34 upon the main-shaft 5.

Upon the rear drum 18 of the hopper-belt 16 are secured the spindles 35 journaled in slide-blocks 36, adjustably disposed in guide-slots, as 37, provided in the side-bars 14 and adjustments of which slide-blocks 36 may be effected in any suitable manner to vary the tension of the belt 16. Pivottally connected with the cross-bar 15 is a supporting-brace 38 adjustably clamped by means of a clamp-lever 39 upon an extension 40 of the machine frame, whereby the rearward end of the hopper may, if desired, be swung about the spindles 19, 20 to incline the belt 16, when necessary under certain conditions to invoke gravity action in the delivery of the needles from the hopper.

Upon the forward drum-spindle 20 is secured a belt-pulley 41 connected by means of a belt 42 with a pulley 43 upon one end of a shaft 44 journaled in brackets, as 45, sustained by the side-bars 14. The shaft 44 carries a plurality of radial needle-agitating fingers 46, a number of which are omitted in Fig. 2 of the drawings to more clearly show other mechanism of the machine. The fingers 46 are preferably spaced from each other a distance less than the length of the needles operated upon and serve primarily to separate the needles of a group or cluster deposited in the hopper.

The needles are delivered by the belt 16 upon an inclined flat-plate 47 having at its opposite sides depending flanges 48 by means of which it is secured upon side-guards 49 sustained by bracket-extensions 50, suitably fixed upon the forward drum-supporting brackets 21. The plate 47 is preferably reinforced by means of an angle-beam 51 suitably secured upon the under side thereof, while a number 65 of baffle-rods 52 project upwardly from said

plate and serve to turn needles dropping transversely from the belt 16.

The needles slide down the inclined plate 47 upon a reciprocating table 53 comprising a wide forward portion in advance of the 70 plate 47 extending the entire width of the machine and a narrowed rearward extension 54. This table 53 is preferably sustained by a plurality of ball-bearings 55 interposed between the under side of the table and the stationary machine frame 2. The forward portion of the table 53 is provided at intervals with longitudinal slots 56 for the reception of guide-bars 57, said slots terminating in shallow grooves 58 formed in the upper surface 80 of the table and affording seats for the narrowed rear ends of the guide-bars 57 which are clamped to their seats by a cross-bar 59 suitably secured upon the table 53. The outer guide-bars are constituted by supporting- 85 plates 60, secured upon the opposite sides of the table 53 and sustaining an adjustable table-extension 61. To this end, said table-extension 61 has its ends slidingly disposed in slots as 62 (only one of which is shown) provided in the supporting-plates 60, the under side of said table-extension being provided at intervals with racks 63. Journaled in the supporting plates 60 below the slots 62 is an adjusting shaft 64 having at its ends the manipulating knobs 65 and provided intermediate its ends with a plurality of spaced gears 66 meshing with the racks 63. This construction permits adjustment of the table-extension 61 relatively to the main-table 53, whereby to provide a needle-point direction determining gap 67 of the desired width between the table and its extension. The provision of this gap 67 constitutes an important feature of the invention, as will hereinafter appear. 95

Certain of the guide-bars, such as 68, may be lengthened to provide additional supporting and guiding slots 69 for the table-extension 61 and to afford additional bearings for the shaft 64. The remaining guide-bars 57 enter slots 70 provided in the table extension 61 in alignment with the slots 56, it being understood from the foregoing description that the main table 53, the guide-bars 57, the table-extension 61 and its adjusting means reciprocate 100 as a unit and that the width of the gap 67 is only altered by manual adjustment of the shaft 64. Preferably a slotted and apertured block 71 is secured upon the outer side of each of the supporting plates 60 to afford a more substantial bearing surface for the parts sustained thereby.

To advance the needles toward the gap 67, the table 53, 54, 61 is reciprocated in one direction by a peripherally-toothed cam 72 secured upon a transverse shaft 73 journaled in a bearing-bracket 74 provided on the frame 2 and in the bearing 4 of the main-shaft 5. The shaft 73 carries a worm-wheel 76 rotated by a worm-gear 76 upon said 110 115 120 125 130

main-shaft 5. Engaging the teeth of the cam 72 is one arm 77 of a bellcrank tappet-lever, fulcrumed upon a bracket 78 and of which the other arm 79 engages a block 80 secured by means of screws, as 81, (only one of which is shown) upon the under side of the rearward extension 54 of the table. A post 82 depends from the under side of the table-extension 54 and this is connected by means 10 of a coil-spring 83 with an adjustable rod 84 passing through an apertured bracket 85 provided on the base of the frame 2. Threaded upon said rod 84 is an adjusting nut 86 determining the tension of the spring 83, which latter functions to impart the forward or advancing movements to the table 53, 54, 61 while the cam 72 acts to retract said table. The arm 77 of the bellcrank-lever is connected by means of a spring 87 with the post 20 82 to insure contact of the other arm 79 of said lever with the block 80.

It will be apparent that while the retracting movement of the table is comparatively slow, the forward movement is very rapid 25 under the action of the spring 83 at the times when each tooth of the cam 72 leaves the arm 77. This rapid advancing movement of the table is suddenly arrested by an adjustable buffer 88 of rubber or other suitable material inserted in the face of a spur-gear 89 carried by a stud 90 threaded into a block 91. The block 91 is secured upon the machine frame 2 by screw-bolts 92 and projects upwardly through a slot 93 formed in the rear 35 table-extension 54. The end wall 94 of said slot 93 constitutes the buffer-engaging element of the table. In order to adjust the horizontal position of the buffer 88, an adjusting spindle 95 has one end journaled in the block 91 and its opposite end in a bearing-block 96 suitably secured upon the machine frame. This spindle 95 carries a pinion 97 meshing with the spur-gear 89 and is manually rotated by means of a crank-handle 98. 40 The spindle 95 is held against endwise movement in any suitable manner and it will be apparent that rotation of said spindle upon manipulation of the crank-handle 98 will cause rotation of the stud 90 within the block 91 whereby the position of the buffer 88 may be varied to increase or decrease the reciprocating movement of the table.

Secured upon the forward end of the machine-frame 2 is a frame-bracket 99 having a curved face 100 affording a seat for the base 101 of a plurality of needle-chutes, of which the side walls are constituted by spaced parallel guide-bars 102 coinciding with the lower edges of the guide-bars 57. The base 101 of the chute is secured by screws as 103 upon the curved face 100 of the bracket 99, the guide-bars 102 being suitably riveted upon said base 101 and further secured in spaced parallel relation by a strap 104 fastened to the frame-bracket 99. The chute-

guideways afforded by the base 101 and the guide-bars 102 are preferably closed at their upper ends by a transverse spacing bar 105 suitably grooved to partially straddle the guide-bars 102, said spacing-bar 105 being 70 secured by screws 106 upon the outer guide-bars 102 and serving as a guard for the needles dropping into the chute-guideways and also to steady the guide-bars 102. The guide-bars 102 are provided with enlarged 75 wedge-shaped lower ends 107.

The frame-bracket 99 sustains a vibratory receptacle-holder 108, it being preferred to interpose series of bearing balls 109 between grooves in said holder and bracket. The receptacle-holder 108 is formed at its opposite longitudinal ends with retaining lugs 110 between which is inserted a receptacle 111 of which one longitudinal edge is seated in a groove 108' provided in the holder. The receptacle has a plurality of compartments formed by dividing walls 112 in alignment with the enlarged ends 107 of the guide-bars 102, whereby during the vibratory movements of the receptacle the walls 112 do not pass beyond said guide-bar ends 107 and consequently do not interfere with the passage of the needles into said compartments. The needle-receptacle and its holder are vibrated in unison by means of a lever 113 of which one end enters a socket 114 provided in the holder and the other end is provided with a fork 115 straddling an eccentric 116 upon the shaft 30. It will be understood that the vibratory movement of the receptacle is extremely small, its only purpose being to aid the needles in settling in their compartments into parallel relationship. A support 117 is preferably provided at the forward end of the bracket 99 for a receptacle to facilitate substitution of an empty receptacle for a full one, while an apron 118 is shown as secured upon the main-frame 2 to catch needles which may accidentally become dislodged in their normal passage through the machine.

In order to start and stop the machine, the pulley 6 is loosely disposed upon the main-shaft 5 and carries a lateral clutch-pin 119 adapted to be engaged by a similar pin 120 provided upon a shift-collar 121. The shift-collar 121 is slidingly keyed upon a flanged bushing 122 for rotation therewith, said bushing being suitably secured upon the main-shaft 5. The shift-collar 121 has a peripheral groove 123 which is engaged by rollers 124 carried by the forked end 125 of a shift-lever 126. The shift-lever 126 is fulcrumed upon the machine frame 2 by means of a pivot-bolt 127 and its outer end is connected by means of a link 128 with a hand lever 129 120 pivotally mounted upon the machine frame.

In the operation of the machine, after a group of needles to be rearranged has been deposited upon the hopper belt 16 rearward of the agitating fingers 46, the machine is start- 130

ed by shifting of the lever 129 to clutch the pulley 6 to the main-shaft 5. This brings the various mechanisms described into operation, whereupon the hopper-belt 16 carries the needles toward the agitating fingers 46, which rotate in the opposite direction. While the fingers 46 serve to some extent to arrange the needles in the direction of travel of the belt 16, they do not approach close enough to 10 the belt to compel this position; their prime function is to separate the needles of the group to prevent delivering a clump of needles to the reciprocating table 53. The belt 16 drops the needles upon the inclined 15 plate 47, the baffle-fingers 52 serving to some extent to turn transverse needles. The table guide-bars 57 are spaced a less distance than the length of the needles and consequently the needles sliding into the guideways afforded by the table 53 and guide-bars 57 are disposed substantially parallel with said 20 guide-bars.

Any needles which may lie transversely across the guide-bars 57 are deflected into the 25 guideways both by the reciprocating movements of the table and by diverting-fingers 130 projecting into the needle guideways and carried by a rod 131. The rod 131 is journaled for oscillation in the side-guards 49 and 30 carries at one end a crank-arm 132 connected to a link 133 pivotally secured upon a lug 134 fastened upon the table 53. Inasmuch as the side-guards 49 are stationary, the reciprocating 35 movements of the table 53 will obviously cause oscillation of the rod 131 whereupon the diverting fingers 130 will dislodge any transverse needles and cast them into the guideways.

The effect of the suddenly arrested movements of the table is such as to advance the 40 needles in their guideways, either point- or shank-first, the speed of advance being regulated by adjustment of the position of the buffer 88. Any needle which approaches the 45 needle-point direction determining gap 67, formed by the spaced and adjustable table-extension 61, shank-first will tilt about the initial edge of the gap as soon as the needle has advanced beyond its center of gravity, 50 which is adjacent the heavier shank-portion of the needle. Consequently such needle will drop shank-first into a chute-guideway and slide down in this position into one of the receptacle-compartments. Should a 55 needle advance point-first, the point will bridge the gap 67 because the heavier shank now prevents tilting of the needle about the initial gap-edge. The point-first needle will thereupon advance upon the table-extension 60 61 until the needle-shank overlies the gap, whereupon the needle tilts about the edge of the table-extension 61 and again drops shank-first into a chute and slides down into a receptacle compartment. As a receptacle 65 compartment fills, the vibratory movement of

the receptacle-holder 108 causes the needles to settle down into parallelism with the points adjacent each other.

It is believed that the present invention is made clear by the foregoing description considered in connection with the accompanying drawings, but it is to be understood that the invention is in no wise limited to the specific details of construction described.

Having thus set forth the nature of the invention, what I claim herein is:—

1. In a needle-picking machine for rearranging a group of needles heavier at the butt-end than at the point, substantially horizontal needle-supporting means provided with a gap defined by spaced walls about which needles advanced thereacross point or butt-end-first turn gravitationally to fall butt-end-first through said gap, and means for advancing needles endwise across said supporting means over said gap.

2. In a needle-picking machine, substantially horizontal needle-supporting means terminating in a wall about which butt-end-first approaching needles turn to gravitationally fall butt-end-first, a needle-supporting extension having a wall spaced from the first-named wall about which needles approaching point-end-first turn to gravitationally fall butt-end-first, said walls defining a gap therebetween through which the needles fall, and guiding means extending across said gap confining the needles to endwise movement upon said supporting means.

3. In a needle-picking machine for rearranging a group of needles heavier at the butt-end than at the point, substantially horizontal needle-supporting and guiding means confining the needles to endwise movement, the needle-supporting means terminating in advance of the end of the guiding means to provide a needle-turning wall about which needles approaching butt-end-first gravitationally fall butt-end-first from said supporting means, and a second needle-turning wall spaced from the other wall, about which needles approaching point-end-first gravitationally fall butt-end-first.

4. In a needle-picking machine, substantially horizontal needle-supporting means provided with a gap defined by spaced walls disposed transversely of the direction of movement of the needles upon said supporting means, means for advancing the needles across said supporting means, and guiding means extending across said gap confining the needles to endwise movement upon said supporting means, whereby needles approaching said gap butt-end-first turn gravitationally about the first approached gap wall and needles approaching point-end-first turn gravitationally about the second gap wall to in both cases fall butt-end-first through said gap, and means for conducting the falling needles endwise away from said gap.

5. In a needle-picking machine, a horizontally disposed reciprocatory table provided with a plurality of adjacent needle guideways confining the needles to endwise movement and with a needle-point direction determining gap intersecting said guideways, means for advancing needles endwise in said guideways to said gap, and means engaging needles transversely overlying the guideways 10 in advance of said gap to divert them into said guideways into substantial parallelism.
6. In a needle-picking machine, needle-supporting means provided with a needle-point direction determining gap, means for advancing needles endwise toward said gap, and means for varying the speed of needle-advancing movement.
7. In a needle-picking machine, needle-supporting means having a needle-point direction determining gap, and adjusting means for determining the width of said gap.
8. In a needle-picking machine, a needle-supporting table, a table-extension spaced from said table to provide a needle-point direction determining gap, and means for relatively adjusting said table and table-extension to vary the width of said gap.
9. In a needle-picking machine, a needle-supporting table, a table-extension spaced from said table to provide a needle-point direction determining gap, adjusting means for varying the width of said gap, and means for reciprocating said table, table-extension and adjusting means in unison to advance needles toward said gap.
10. In a needle-picking machine, a reciprocatory table provided with a needle-point direction determining gap, means for directing needles endwise toward said gap, and means for reciprocating said table to advance said needles including a buffer for arresting the movement of said table in one direction, and means for advancing the table to engage said buffer.
11. In a needle-picking machine, a reciprocatory table provided with a needle-point direction determining device, a buffer, yielding means for rapidly advancing said table into engagement with said buffer to arrest 50 the movement of said table in one direction, a rotary actuating element for retracting said table, and means for adjusting the extent of advancing movement of said table.
12. In a needle-picking machine, a needle-supporting table provided with a needle-point direction determining device, and means for reciprocating said table to advance needles thereacross including a buffer, a buffer-block, a buffer carrying stud threaded into said buffer-block, a buffer-adjusting rod, 55 and gear connections between said rod and stud to vary the position of said buffer.
13. In a needle-picking machine, a reciprocatory table provided with a plurality of adjacent needle-guideways and with a needle-point direction determining gap intersecting said guideways, means for advancing needles in said guideways to said gap, a plurality of needle-diverting fingers disposed to engage needles positioned transversely of said guideways, and means for actuating said diverting fingers.
14. In a needle-picking machine for rearranging a group of needles heavier at the butt-end than at the point, a needle-hopper 75 having a base moving in a continuous direction for delivering needles therefrom, means for actuating said hopper base, adjustable means for inclining said base to the horizontal to control the speed of delivery of the 80 needles therefrom, a reciprocating table receiving the needles delivered by said hopper-base including guiding means confining the needles to endwise movement across said table, means for reciprocating said table to 85 advance the needles thereacross, said table terminating in a wall disposed transversely of the direction of travel of the needles about which wall needles approaching butt-end-first turn to gravitationally fall butt-end-first, a table extension having a wall spaced from the first-named wall about which 90 needles approaching point-end-first turn to gravitationally fall butt-end-first, said walls defining a gap therebetween through which 95 the needles fall.

In testimony whereof, I have signed my name to this specification.

MAXWELL L. REIDINGER.
